UNITED STATES PATENT OFFICE

2,584,374

BOWLING TIME CLOCK

Milford L. Wickstrom, Kansas City, Kans.

Application September 12, 1949, Serial No. 115,253

3 Claims. (Cl. 161—17)

1

This invention relates to the field of recreation and particularly to the game of bowling, the primary object being to provide a timing device for indicating to the players and others whether or not the frames and games are being played according to schedule with respect to time consumed.

Bowling alley operators are universally confronted with the problem of groups of players failing to continue with their playing without delay, thereby finishing with a particular game, or series of games within a reasonable time. In the absence of completion within a given time, following groups are delayed and cannot finish at a contemplated hour. For instance, a "league" of three games, scheduled to commence at six p. m. should be finished at approximately eight-fifteen p. m. whereby succeeding groups can be assured of commencing at about eight-thirty p. m. If the second "league" of games is late in starting, completion thereof will be much later than expected to the disadvantage of all concerned.

To continuously call the player's attention to their delay is embarrassing to them and to the alley owner and often results in misunderstandings and ill feeling. Accordingly, it is the most important object of the present invention to present a timing device to the players capable of indicating to them at all times whether or not they are playing at the speed necessary to finish on schedule.

Another important object of this invention is to provide a clock-like apparatus having means to indicate at any moment the exact frame of a particular game within which the players should be bowling.

Another object is to provide a clocking means for bowling alleys showing the league of games, the game of the league, and the frame of the game in which the bowlers should be playing at any particular moment.

Other objects of this invention include the way in which the dial of the clock-device is set off to effect all of the indicating functions above set forth as can be more adequately outlined in the following specifications.

In the drawing:

Fig. 1 is a front plan view of a bowling alley clock made in accordance with the present invention; and,

Fig. 2 is an inverted plan view thereof, parts being broken away for clearness.

Conventional clock mechanism without a housing 10 is employed in the device about to be described and has therefor not been shown. Such

2

mechanism is provided with means to rotate an hour hand 12 a complete revolution in twelve hours and to rotate a longer minute hand 14 one revolution in one hour in the usual manner.

5 Hands 12 and 14 are disposed to traverse face 16 of a circular, disc-like dial 18 that is mounted on a support 20 within which is disposed housing 10. The entire assembly is preferably mounted in an elevated position, easily seen by all concerned through any suitable structure (not shown).

Face 16 of dial 18 has printed, painted or otherwise calibrated thereon a continuous, elongated spiral 20 commencing at one end 22 thereof adjacent the periphery of dial 18 and terminating at the opposite end 24 thereof adjacent the center of face 16. A continuous line 26, extending from end 22 to end 24 sets off said spiral 20 which is made up of a large number of convolutions.

20 Spiral 20 is set off into two groups 28 and 30, each having a number of elongated, arcuate segments. Group 28 is provided with segments 32, 34 and 36 and group 38, 40 and 42. The segments 32, 34, 36, 38, 40 and 42 are each in turn set off

25 by radial lines 44 into ten divisions each and designated by the numeral 46. It is noted that each division 46 of each segment is of the same length but that the divisions 46 progressively decrease in length from segment 32 to segment 42. The divisions 46 of each segment are numbered from 1 to 10 inclusive by indicia 48, in the clockwise direction of rotation of hands 12 and 14. Thus, the division 46 of segment 32 having the indicia "1" thereon is adjacent end 22 of spiral 20 and division 46 of segment 32 having indicia "10" thereon is next adjacent the division 46 of segment 34 having indicia "1" thereon.

30 Group 28 is separated from group 30 by an elongated, arcuate section 50 between proximal divisions 46 of segments 36 and 38. Area 50 has the words "league change" printed thereon as at 52. Divisions 46 refer to bowling frames as indicated by indicia 54 and indicating hand 56 forwardly of end 22 of spiral 20.

35 It is noted that end 24 of spiral 20 terminates radially outwardly of hand 12. A space 58 at the center of dial 18 is provided with three, relatively short, arcuate areas 60, 62 and 64, each divided into three equal portions 66 by radial lines 68.

40 Portions 66 are numbered consecutively by indicia 70, and refer to games of bowling as indicated at 72.

45 The clocking device above described contemplates two leagues of three games each in approximately four hours and forty-five minutes

which permits forty-five minutes for each game and fifteen minutes between groups of three games each. Thus, each frame should be played in four and one-half minutes.

Assuming hand 14 to be overlying division 46 of segment 32 having indicia "1" thereon at the start of play, hand 12 will be approaching portion 66 of area 60 having indicia "1" thereon. When hand 14 reaches division 46 of segment 32 marked "10", forty-five minutes will have elapsed and hand 21 will have approached to portion 66 of area 60 marked "1", indicating that the first game, including 10 frames, has been or should be completed.

When hand 14 has reached division 46 of segment 34 marked "10," ninety minutes will have elapsed and two games should be completed which will be indicated by hand 12 over area 60.

At the end of the third game, hand 14 will traverse section 50, during which time (fifteen minutes) the bowling alley attendants will have sufficient time to prepare the alleys and attend to other matters preparatory to the following three games. Such games are indicated from standpoint of time by hand 14 corresponding to segments 38, 40 and 42 while hand 12 corresponds to area 62.

Thus, area 60 clocks the three games between six p. m. and eight-fifteen p. m., for instance, and area 62 clocks the games between eight-thirty p. m. and ten forty-five p. m. Area 64 may be utilized for morning or afternoon games.

While two groups 28 and 30 have been shown, the number of such groups may be increased or decreased as desired. Each of the segments 32, 34, 36, 38, 40 and 42 is preferably given a distinguishing color and the portions 66 corresponding thereto are colored accordingly, for facilitating reading of the dial 18 quickly and easily at a glance.

It is further contemplated that dial 16 be also provided with the usual clock face indicia on the marginal edge of face 16 whereby the hands 12 and 14 serve the additional function of keeping the players informed of the time.

Having thus described the invention, what is claimed as new and desired to be secured by Letters Patent is:

1. In a timing device for bowling games having timepiece mechanism including a rotatable hour hand and a rotatable minute hand, a dial for the hands comprising a member having a face underlying said hands, said face having an elongated spiral formed thereon within the space traversed by the minute hand only, said spiral having a number of divisions, each corresponding in length with the distance of travel of said minute hand during a single bowling frame

played at a predetermined speed, said face having an arcuate area thereon within the space traversed by said hour hand, said arcuate area having a number of portions, each corresponding in length with the distance of travel of said hour hand during a bowling game of ten frames played at a predetermined speed.

2. In a timing device for bowling games having timepiece mechanism including a rotatable hour hand and a rotatable minute hand, a dial for the hands comprising a member having a face underlying said hands; said face having an elongated spiral formed thereon within the space traversed by the minute hand only, said spiral having a number of divisions, each corresponding in length with the distance of travel of said minute hand during a single bowling frame played at a predetermined speed, said face having an arcuate area thereon within the space traversed by said hour hand, said arcuate area having a number of portions, each corresponding in length with the distance of travel of said hour hand during a bowling game of ten frames played at a predetermined speed, said spiral having a number of segments, each comprising ten of said divisions.

3. In a timing device for bowling games having timepiece mechanism including a rotatable hour-hand and a rotatable minute-hand, a dial for the hands comprising a member having a face underlying said hands, said face having an elongated spiral formed thereon within the space traversed by the minute-hand only, said spiral having a pair of sections each divided into three segments and each segment respectively being sub-divided into divisions, each division corresponding in length with the distance of travel of said minute-hand during a single bowling frame played at a predetermined speed, said face having an arcuate area for each section respectively within the space traversed by said hour-hand, each area having a portion for each segment respectively and corresponding in length with the distance of travel of said hour-hand during a bowling game of ten frames played at a predetermined speed.
